CLAIM

The ornamental design for a carry lantern as shown and described.

DESCRIPTION

FIG. 1 is a perspective side view of a carry lantern showing my new design;

FIG. 2 is a front view;

FIG. 3 is a rear view;

FIG. 4 is a right side view;

FIG. 5 is left side view;

FIG. 6 is top view; and,

FIG. 7 is a bottom view.

The broken lines shown illustrate portions of the carry lantern that form no part of the claimed invention.

1 Claim, 7 Drawing Sheets
